DESIGN FOR A DOLL

Edith S. Holden, New York, N. Y.

Application April 26, 1939, Serial No. 84,569

Term of patent 14 years

To all whom it may concern:

Be it known that I, Edith S. Holden, a citizen of the United States, residing at 14 East 60th Street, New York city, in the county of New York and State of New York, have invented a new, original, and ornamental Design for a Doll, of which the following is a specification, reference being had to the accompanying drawing, forming part thereof.

Figure 1 is a front elevational view, Figure 2 is a perspective view, and Figure 3 is a side elevational view of a doll in an inclined position, showing my new design.

I claim:

The ornamental design for a doll, substantially as shown.

EDITH S. HOLDEN.
